UNITED STATES PATENT OFFICE.

HERBERT E. WHITE, OF YOUNGSTOWN, OHIO, ASSIGNOR TO THE GENERAL FIREPROOFING COMPANY, OF YOUNGSTOWN, OHIO, A CORPORATION OF OHIO.

PROCESS FOR MAKING EXPANDED-METAL STRUCTURES.

1,212,863.

Specification of Letters Patent.

Patented Jan. 16, 1917.

Application filed June 14, 1913. Serial No. 773,651.

To all whom it may concern:

Be it known that I, HERBERT E. WHITE, a citizen of the United States, residing at Youngstown, in the county of Mahoning and State of Ohio, have invented certain new and useful Improvements in Processes for Making Expanded-Metal Structures, of which the following is a specification.

The present invention relates to a novel and practical process for making expanded sheet metal structures, particularly of the type known as metal lathing.

The object of the invention is to provide a process that may be successfully and commercially employed to slit and expand inside areas of a metal sheet, that is between the ribs, or plain unslotted areas, without buckling or otherwise producing a contraction or distortion of said ribs or plain areas during the slitting, stretching, and expanding operations. And, to this end, the present invention distinguishes from those processes wherein the slitting and expanding is worked from an external edge of the blank inwardly, in the particular that the same involves making a field of rows of interrupted longitudinal slits in the metal sheet between the non-contractible blank areas or ribs, causing the strands formed by the slits to be longitudinally elongated or stretched and uniformly pressed, to the same extent of projection, to one side of the plane of the sheet, and subsequently pulling the sheet laterally to thereby deploy or move the stretched strands into open meshes of novel and useful form.

From a practical standpoint, it has been found necessary and desirable to simultaneously perform the slitting and stretching operations, otherwise the stretching is likely to be localized in the weakest part of the strand, resulting in an unduly high percentage of breakage. This condition imposes the necessity of making at sometime during the cutting and stretching operation at least two parallel cuts simultaneously, and this procedure provides internal edges from which to work outwardly in cutting and stretching additional strands.

Accordingly, the present invention takes into consideration, and includes as important and practical features thereof, the stretching of the strands simultaneously with the slitting or cutting operation, and the production of internal edges from which

proceed the progressive cutting and stretching of additional strands until the entire predetermined field or area is slotted, stretched, and partly expanded.

In carrying out the process any suitable instrumentalities or mechanisms may be employed which are available, or can be adapted, for the purpose, so for illustrative purposes there are only shown in the drawings, diagrammatically, such views as may be necessary for a full understanding of the manipulation of the metal sheet to develop and produce, in a rapid and economical manner, the expanded metal structure.

In these drawings Figure 1 is a diagram illustrative of one arrangement of die positions that may be followed in carrying out the invention. Fig. 2 is a plan view of a partially slit sheet metal blank showing the progressive action of the dies having the order shown in Fig. 1. Fig. 3 is a detail cross sectional view on the line 3-3 of Fig. 2 illustrating the action of the dies c-c in Fig. 1. Fig. 4 is a similar view on the line 4-4 of Fig. 2 illustrating the action of the dies d-d for the outermost cuts; this line of section also appearing on the line 4-4 of Fig. 5. Fig. 5 is a plan view of a sheet metal blank having areas thereof slotted, stretched, and partly expanded according to the steps illustrated by Figs. 1, 2, 3 and 4. Fig. 6 is a longitudinal sectional view on the line 6-6 of Fig. 5. Figs. 7, 8 and 9 are plan, longitudinal sectional, and cross sectional views respectively of the finished product formed by laterally spreading the sheet shown in Fig. 5; the Figs. 8 and 9 being sections on lines 8-8 and 9-9 of Fig. 7. Fig. 9 is a cross sectional view of the finished product having ribs between the slotted and expanded areas and reinforce beads at the outer marginal edge of the latter; the line of section being indicated by line 9a-9a on Fig. 7. Figs. 10 and 11 are diagrammatic plan and longitudinal sectional views respectively (Fig. 11 being on the line 11-11 of Fig. 10), illustrating a modification in the order of the action of the dies to produce the preliminary corrugated shape. Fig. 12 is a view similar to Figs. 2 and 10 showing another modification in the order of the action of the dies. Fig. 13 is a plan view of a completely slotted, stretched, and corrugated sheet produced according to the action of dies illustrated in

Fig. 12. Fig. 14 is a longitudinal sectional view on the line 14—14 of Fig. 13. Fig. 15 is a cross sectional view on the line 15—15 of Fig. 13. Figs. 16, 17, 18, and 19 are views similar to Figs. 12, 13, 14, and 15, but illustrating a special cutting and offsetting which displaces slotted corrugations to both sides of the plane of the sheet.

Like reference characters designate corresponding parts in the several figures of the drawings.

As stated, the present invention contemplates slitting, stretching, and expanding a metal sheet between at least two ribs, or between at least two non-contractible unslotted areas, without buckling, or otherwise producing a contraction of said ribs or said areas during these operations. This may be performed with any suitable mechanism or apparatus available for the purpose, but preferably by means of combined cutting and displacing dies have the structural and functional characteristics, for instance, of the dies disclosed in the patent to this applicant, #1,049,632, dated Jan. 7, 1913. However, the precise arrangement of such dies would necessarily vary according to the exact progression of the cuts or slits to be made in the metal sheet, and as the mounting and handling of dies of this character may be readily understood by reference to the patent aforesaid, there is shown in Fig. 1 of the drawings, a diagram illustrative of one arrangement of die positions that may be followed in carrying out the invention.

Referring to said diagram of Fig. 1 it will be observed that a minimum number of dies are indicated for the sake of clearness, and said dies preserve a progressive order so as to successively come into action and at the same time to jointly provide for cutting all of the slits in the metal sheet and displacing or offsetting the strands formed thereby to one side of the plane of the sheet. According to the diagram, the set of dies includes a primary center die *a*, and progressively arranged, or successive, pairs of parallel dies *b*—*b*, *c*—*c*, and *d*—*d*, and so on to any desired number of such pairs of dies, as may be required. The first stage in the manipulation of the metal sheet between these dies is to cut into the sheet, at the center of the space to be slitted, a middle series of longitudinal interrupted slits, designated by the numeral 1 in Fig. 2 of the drawings. This middle line of interrupted slits is produced by the action of the primary center die *a*, and the operation involved is merely that of slitting. Then, the series of central slits 1 is succeeded by the formation of other rows or parallel longitudinal interrupted slits, designated respectively by the numerals 2—2, 3—3, and 4—4, and which are respectively produced by the action, successively, of the pairs of dies *b*—*b*, *c*—*c*, and *d*—*d*, of

the die set. The metal sheet is thus cut with parallel lines of interrupted slits arranged alternately in adjacent lines so that the slits in each row thereof are disposed in staggered relation to the slits of parallel adjacent rows. This is shown in Fig. 5 of the drawings which illustrates a metal sheet that has been slitted, stretched, and partly expanded by the action of the combined cutting and displacing dies, preparatory to subjecting the sheet in that condition to the subsequent lateral spreading or expanding operation for pulling the stretched and offset strands to form full-open meshes.

Referring more particularly to the progressive action of the slitting, stretching, and displacing operation, it will be observed, according to the order of cuts prescribed by the arrangement, shown in Figs. 1 and 2, that the production of the central slits 1 does not include an accompanying stretching action, and that the first pair of dies *b*—*b* also merely cut the material to produce the first pair of slits 2—2 respectively upon opposite sides of the central slit 1. But, the next succeeding pair of dies *c*—*c* are closer together than the preceding dies *b*—*b*, and are so arranged as to cut the metal sheet midway of the space between the central starting slit 1 and the first pair of starting slits 2—2 and in alternating or staggered relation thereto, as best seen in Fig. 2 of the drawings. Also, the said dies *c*—*c* are of a suitable form and have the proper movement to effect a displacing or offsetting of the metal strands formed by and between the slits 3—3. Accordingly, the action of the dies *c*—*c* is to produce the slits 3—3 in the sheet, and to depress all the material therebetween to one side of the plane of the sheet, with a consequent stretching or longitudinal elongation of such material.

When the stretched and offset strands between the slits 3—3 are brought into the zone of action of the next succeeding dies *d*—*d*, these dies produce the outer slits or cuts 4 in alternating or staggered relation to the previous slits or cuts 2. At the same time, said dies stretch and offset to one side of the plane of the sheet the intervening strands of material between the slits 2 and 3 and the slits 2 and 4, which strands of material include the unslotted terminal connecting webs 5 between the adjacent ends of two of the slits 2 lying in the transverse plane 120 of the slits 4 which are made by the dies *d*—*d*. By means of other similarly or equivalently arranged pairs of dies, the operation may be repeated to the required extent, according to the width of area to be slitted, stretched, and partly expanded.

When the area between the non-contractible unslotted areas or ribs is completely slitted, stretched, and partly expanded, according to the order above described, the 130

sheet has the formation shown more clearly in Figs. 5 and 6 of the drawings, wherein the stretched and offset strands have uniform projection to one side of the plane of the sheet, and form what may be termed uniform transverse slitted corrugations or regular undulations, with the slits closed or substantially closed, and the ridges of which corrugations are in the transverse plane of the particular ones of the unslit webs 6 which connect the outermost strands in each slitted area with the margins of the unslitted areas or ribs of the metal sheet, as plainly shown in both Figs. 5 and 6 of the drawings. In other words, the step of the process, so far described, produces an unopened undulated slitted area between the blank or ribbed areas with the slits in a substantially closed condition, so that, in order to complete the material, it is necessary by any of the well known instrumentalities suitable for the purpose to spread or expand the sheet laterally. This operation opens up the slits and pulls or deploys the stretched strands apart to give the meshes their final form and size.

The result of the final step of the process is illustrated by the group of Figs. 7, 8, and 9, of the drawings. Referring more particularly to the plan and sectional views of Figs. 7 and 9, it will be noted that when the material in its unopened corrugated form, as shown in Figs. 5 and 6, is pulled, drawn, or spread laterally, the various unslitted terminal and side connecting webs 5 fold or crease in line with the cuts and hence become hinging points or axes upon which the stretched strands *s* turn or twist to positions which are inclined or oblique to the horizontal plane of the sheet, and thereby producing what may be termed concavo-convex lanceolate meshes which provide effective keys for the cementitious material. It will now be apparent that in the finished product, the expanded or open meshes thereof are not only of lanceolate shape, but are concavo-convex or dished, and each mesh consists of opposite bent walls (formed by stretched strands *s*) converging toward both ends of the mesh where they unite with the ends of the contiguous meshes in the same row, and at its center, each mesh wall is joined to the laterally adjacent wall of the mesh in the same transverse row. Furthermore, as already made, the mesh walls are disposed at an inclination or obliquely to the flat plane of the sheet to produce the dished effect and the lanceolate meshes. Also, the meshes in the adjacent longitudinal rows thereof are in staggered relation, and alternately reversed so as to respectively present their concaved and convexed side portions at opposite sides of the sheet, as may be best seen from Fig. 7 of the drawings.

As shown in Fig. 9^a, without altering at all these characteristics of the slitted and expanded areas of the product, it will be understood, as stated that the said slitted and expanded areas alternate with plain unslitted areas, as shown in Figs. 7, 8 and 9⁷⁰ of the drawings, or with ribs *r*, as shown in Fig. 9^a of the drawings. It is also preferable in producing the ribbed product to form back-turned reinforce beads or flanges *f* by the means shown, for instance, in my Patent No. 1,125,786, dated Jan. 19, 1915.

The order and action of the dies in performing the step of slitting, stretching, and displacing the metal is subject to change without altering the process proper. To illustrate this, there is shown in Figs. 10 and 11 of the drawings, a metal sheet operated upon by an arrangement of the dies wherein the primary center die may be omitted so that the first stage in the manipulation of the sheet is to produce within the central portion thereof, a pair of slits 2 and to simultaneously depress the strand of material *s* therebetween. This may be followed successively by the production of the outermost slits 4 and a stretching and depressing of all of the intervening strands *s* therebetween, and then subjecting the uniform slitted corrugations thus produced to the further slitting action of dies to form intermediate rows of the interrupted slits 1 and 3 alternating with the slits 2 and 4 in staggered relation, thus producing precisely the same unopened transversely corrugated slitted area, whose corrugations have a uniform projection from the body of the sheet, so that the final step of the process to open up or deploy the strands remains the same as already described. Again, as suggested in Figs. 12, 13, 14, and 15, the arrangement of dies may be such as to produce the line of interrupted central slits 1 as the first stage of the process, next to produce a pair of slits 2—2 respectively upon opposite sides of the center slit, and to simultaneously stretch and offset the intervening strands of material *s*. Then to follow with an intermediate pair of slits 3—3 between and alternating with the center slit 1 and the pair of slits 2—2, but without further displacing or offsetting of the strands, and finally to produce outer slits 4—4, and to simultaneously depress the marginal strands *s'* next to said slits, and all of the intervening unopened corrugated slitted material formed between the preceding slits 1, 2, and 3. The effect of this is to produce, along the side margins of the slitted area, open meshes *s*² having substantially the form and size of the finished meshes when drawn into their final position by the lateral spreading or expanding of the sheet. In other respects, the process remains the same as already described, and

the partly finished product shown in Fig. 13 of the drawings is subjected to the final step of lateral spreading which opens up the said unopened slotted corrugations.

5 In the several phases of the invention so far described, the same exhibit the preferable feature of pressing all of the cut and stretched strands to one side of the original plane of the sheet rather than to press part 10 to one side and part to the other, as such preferred arrangement produces a sheet that is more easily handled without injury and which may be more readily spread laterally. But, it is intended that the present process 15 shall apply to the production of a sheet wherein the action of the dies is such that part of the stretched strands may be pressed to one side of the plane of the sheet, and part to the other side of the plane of the 20 sheet. The result of such action in the die cutting and pressing step is suggested in Figs. 16 to 19 inclusive of the drawings, wherein it will be observed that the center line of stretched strands s formed between 25 the intermediate slits 3-3 and 1-1 are pressed to one side of the plane of the sheet, while the remaining strands $s-s$ formed between the slits 2, 3 and 4 are pressed to the other side of the plane of the sheet. Yet 30 these oppositely projecting strands lie in the same transverse plane and have a uniform projection from the plane of the sheet, and also preserve the feature of regular or uniform unopened transverse slotted corrugations, so that necessarily the final step of 35 the process and its resultant effect is precisely the same with this modified preliminary shape as with the other preliminary shapes already described.

40 I claim:—

1. The method of making expanded metal structures which consists in slitting the portion of the blank to be expanded, stretching longitudinally the metal of the strands 45 formed by the slits and deforming the slitted

and stretched material into unbroken undulations, and subsequently spreading the blank laterally to thereby open the slits into meshes.

2. The method of making expanded metal structures which consists in longitudinally slitting the portion of the blank to be expanded, stretching longitudinally the metal of the strands formed by the rows of slits and deforming the slitted and stretched material into unbroken undulations displaced to the side of the blank, and then acting on the blank to cause the displaced portion to spread, thereby opening the slits into meshes. 50

3. The method of making expanded metal structures which consists in longitudinally slitting the portion of the blank to be expanded, and, simultaneously with the slitting operation, stretching the metal of the strands formed by the slits and deforming the slitted and stretched material into unbroken undulations, without opening the slits, and subsequently spreading the sheet laterally to thereby open the slits into meshes. 55

4. The herein-described method of opening portions of a sheet blank into expanded metal open-work comprising meshes of substantially diamond form, which consists in slitting the portion to be expanded, and, simultaneously with the slitting operation, stretching the strands formed by the slits and deforming the slitted and stretched material into unbroken undulations, and then acting on the blank to cause the stretched and deformed portion to be opened into meshes and thereby brought into a widened plane. 60

In testimony whereof I hereunto affix my signature in the presence of two witnesses. 65
